UNITED STATES PATENT OFFICE.

HERBERT D. HOUGH, OF CRANSTON, RHODE ISLAND, ASSIGNOR TO WIGHTMAN & HOUGH COMPANY, OF PROVIDENCE, RHODE ISLAND, A CORPORATION OF RHODE ISLAND.

CIGARETTE-CASE.

1,170,067.

Specification of Letters Patent.

Patented Feb. 1, 1916.

Application filed December 14, 1914. Serial No. 877,040.

To all whom it may concern:

Be it known that I, HERBERT D. HOUGH, a citizen of the United States, and resident of Cranston, in the county of Providence 5 and State of Rhode Island, have invented certain new and useful Improvements in Cigarette-Cases, of which the following is a specification.

This invention relates to cigar or cigarette cases of the class having a holder between the lids for supporting the contents of the case, and the object of the invention is to provide simple, practical and effective means for opening the lids when released by 10 the catch, supporting the holder in medial position between the lids when open, and also for normally retaining the members of the holder in closed position to grip and support the contents of the casing. By this 15 construction the cigarettes are presented in an upright position relative to the lids rendering them very accessible and in position to be drawn out endwise from the holder.

With these and other objects in view, the 20 invention consists of certain novel features of construction, as will be more fully described and particularly pointed out in the appended claims.

In the accompanying drawings: Figure 25 1— is a perspective view showing the casing in open position and the holder centrally supported between the lids and retaining a plurality of cigarettes. Fig. 2— is a side elevation with one of the lids removed showing 30 the mechanism for operating the holder and the latter as being filled with cigarettes. Fig. 3— is a greatly enlarged side elevation of the holder and the mechanism for operating the same. Fig. 4— is a sectional end 35 elevation on line A—4 of Fig. 3. Fig. 5— is an end view of the holder showing the arrangement of flutes or recesses therein, whereby the cigarettes are held to over-lap each other, so as to reduce the width of the 40 casing to the minimum which is designed to carry a given number of cigarettes. Fig. 45 6— is a perspective view of one of the standard members designed to support the holder.

50 Referring to the drawings 9 and 10 designate the two lids of the casing, which are preferably formed concave and are hinged together as at 11 by the passing of the usual hinge spindle 12 through alternate eyes 13 and 14 connected to the opposite lids.

It is found in practice very desirable to provide a holder in a casing for supporting the cigarettes in a medial position when the casing is opened so as to present the contents in a most convenient position to be 50 easily removed therefrom, and also to facilitate the loading of the holder when empty. In the construction of such a holder I have formed two side members 15 and 16 both of which are oppositely fluted at 7 and 65 8. Their lower portions being turned inwardly as at 17, see Fig. 4, to form a bottom to the holder, the upper portion of the holder being left open to receive the cigarettes 70 a into the recesses or sockets formed by the flutes, and I have hinged these two members together at 18 and 19, see Figs. 2 and 3, whereby they may be swung open sufficiently to readily receive the cigarettes 75 and then closed against the same to bind and hold them in position by action of the springs presently described. This holder is supported on a pair of standards 20 pivotally mounted on the hinge spindle 12, the upper end 21 of each being turned at an 80 angle, see Fig. 6, and on which portion the member 15 of the holder is rigidly secured. In order to provide the necessary actions or movements to this holder, I have provided 85 a pair of simple bow-shaped springs 22 and 23, one connected to the outer edge of each of these holder members. The middle of the spring 22 is connected by the eye member 24 to the holder member 15 and its ends are slidably supported in the eye members 26 90 attached to the lid 9, while the middle portion of the spring 23 is connected to the opposite holder member 16 by the eye 27 and its opposite ends 28 are loosely mounted to slide endwise in the eyes 29 fixed to the 95 flange portion of the lid 10. By this simple and practical arrangement of the two bow-shaped springs I perform the following functions. First:—The action of these springs upon the lids causes them to immediately open when released by the catch 30, the extent of which opening is limited to the bringing up of the edges at the back of the lids against each other. Second:—These 100 springs acting on the outer edges of both of the holder members 15 and 16 serve to raise and support the holder centrally between the lids. Third:—The mounting of the spring on the outer edges of the holder members serve to press these holder mem- 110

bers together and normally retain them in closed position to engage and support the cigarettes held between them and at the same time providing sufficient yieldability 5 to permit the members to be swung apart on their hinges as illustrated by the dotted lines in Fig. 4, when it is desired to load the holder.

As illustrated in Fig. 5 the flutes of the 10 holder are set somewhat staggering or out of transverse alinement with each other so that the cigarettes which are formed oval or oblong in cross section when placed therein instead of setting edge to edge are caused 15 to overlap each other thereby reducing the width of casing to the minimum for receiving a given number of cigarettes.

My improved device is extremely simple 20 in construction and practical in its operation.

While I have shown and described the invention as applied to a cigarette case it will be understood that the invention is adapted for use in other similar articles where it is 25 desired to support a holder in central position when the lids of the case are in open or closed position, such for example as vanity cases, card-cases, match-cases, coin holders and the like. It will be understood that I 30 do not wish to limit myself to the precise construction shown and described as changes may be made in the details of construction without departing from the spirit and scope of the invention.

35 I claim:

1. A case of the character described comprising a pair of hinged lids, a standard mounted on a hinge between said lids, a holder attached to said standard, and 40 springs interposed between the lids and the holder to open the lids and bearing on the holder to centralize the same.

2. A case of the character described comprising a pair of hinged lids, a standard 45 mounted on the lid hinge, a holder attached to said standard, and springs interposed between the lids and the holder to open the lids and bearing on the holder to centralize the same.

50 3. A case of the character described comprising a pair of hinged lids, a standard mounted on a hinge between said lids, a holder attached to said standard, flexible wires disposed lengthwise of the hinge and 55 located on opposite sides of the holder, and interposed between the lids and the holder to open the lids and bearing on the holder to centralize the same.

4. An article of the character described 60 comprising a pair of hinged lids, a holder formed of two pivoted side members

mounted between said lids and flexible means interposed between each side member and its adjacent lid and acting to retain said side members in closed position. 65

5. A case of the character described comprising two lids hinged together, a holder constructed of two side members hinged together between the lids, and a spring interposed between each side member and each lid to open the lids close said side members and centralize the holder. 70

6. An article of the character described comprising two lids hinged together, a holder pivotally mounted between the lids 75 and comprising two separable side members each having an inwardly turned bottom portion and a spring interposed between the bottom portion of each side member and the adjacent lid. 80

7. An article of the character described comprising two lids hinged together, a holder formed of two side members mounted to swing on the lid hinge, a spring interposed between each member of the holder and its adjacent lid, said spring being arranged and adapted to move the lids to open position, to support the holder in central position when the lids are in open position, and to hold said members in closed position. 90

8. An article of the character described comprising a pair of hinged lids, a holder mounted between said lids and spring wires extending lengthwise of the hinge and engaging said lids and holder, the points of engagement of the holder with the spring wires on opposite sides of the hinge being spaced from each other a distance substantially equal to the distance between the points of engagement of the lids with said spring wires on opposite sides of the hinge in all relative positions of the lids. 100

9. An article of the character described comprising a pair of hinged lids provided with spring-engaging members, a holder hinged between said lids and also provided with spring engaging members, and spring wires extending lengthwise of the hinge and attached to the spring-engaging members of the holder and the lids, the spring-engaging members of said holder on opposite sides of the hinge being spaced from each other a distance substantially equal to the distance between the spring-engaging members of said lids on opposite sides of the hinge in all relative positions of the lids. 110

In testimony whereof I affix my signature in presence of two witnesses.
